UNITED STATES PATENT OFFICE.

JAMES W. DUNHAM, OF NEW YORK, N. Y.

LAMP-SHADE.

1,130,496.

Specification of Letters Patent.

Patented Mar. 2, 1915.

Application filed July 17, 1914. Serial No. 851,543.

To all whom it may concern:

Be it known that I, JAMES W. DUNHAM, a citizen of the United States, residing at New York, in the county of New York and State of New York, have invented certain new and useful Improvements in Lamp-Shades, of which the following is a specification.

This invention relates to lamp shades and 10 with regard to certain more specific features thereof to shades for incandescent lamps in which the shade is adapted to have a substantially universal movement with respect to the longitudinal axis of the lamp to permit the shade to be adjusted to any desired 15 angular position relative thereto.

One of the objects of the present invention is to provide a simple and practical lamp shade which will be cheap to manufacture.

A further object is to provide a lamp shade of the above character which will be reliable and efficient in use, and is so designed as to prevent breakage of the lamp bulb as the shade and lamp are moved relatively to each other.

Other objects will be in part obvious and in part hereinafter pointed out.

The present invention accordingly consists in the features of construction, combination of elements and arrangement of parts which will be exemplified in the device hereinafter described, and the scope of the application of which will be indicated in the following claims.

In the accompanying drawing, wherein is illustrated one of various possible embodiments of the present invention: Figure 1 is a side elevation, partly in section, of the complete device, and showing in dotted lines the relative position of the shade and bulb when moved from vertical position; Fig. 2 is a detailed perspective view of the gripping arms.

Similar reference characters denote corresponding parts in both figures.

Referring now to the drawing in detail there is denoted at 5 a lamp shade of metal or colored glass of any desired shape but preferably substantially as shown, as the same will more conveniently fit an electric light bulb 6, with which it is preferably adapted to be used. This shade is provided with a central opening 7 through which passes a threaded stud 8, engaging a nut 9,

for securing the bulb gripping device to the shade. This gripping device as herein shown comprises a plurality of similar irregularly bent arms adapted to engage the bulb at a plurality of points in contradistinction to a gripping device, which might be used and engage the bulb by a line of surface contact such as might occur by a wire bent in the form of a ring of a relatively flat band. These arms it will be noted are preferably made from a pair of wires having a twisted central connection with each other and spaced apart to engage the bulb along imaginary longitudinal lines substantially 90° apart, although it is of course to be understood that more arms may be used if desired, although the present construction is believed to be more advantageous, as it permits a more rapid and convenient removal or application of the shade to a bulb. It further permits the shade to be turned relatively to the bulb as may be desired, as shown by the dotted lines, with greater ease.

The arms engaging the upper and lower parts of the bulb at single points thereby protect the end point 12 of the bulb 6. Should it be attempted to make the gripping device so as to have a line or surface contact with the bulb there will be a decided tendency to snap off this point 12 when the shade and bulb were moved relatively to each other, which will of course destroy the usefulness of the bulb.

It is thought the method of use and operation of a device of this character should be clear from the above description. It may be stated however, that the shade is particularly adapted for use in connection with a portable electric lamp of the general type shown in pending application of W. P. Dunham, Serial Number 833,340, filed April 21, 1914, in which case the bulb 6 is received in a socket 13, having a ball and socket joint 14, with a portable standard 15. The lamp shade is forced thereover to spring the yielding arms 10 and 11 outwardly, so that they subsequently grip the bulb at the points 16 and 17 of each arm. Then when the lamp is swung over as shown by the dotted line position the shade may be turned relatively thereto without danger of breaking the tip 12. It is thus seen that the present invention provides a simple and practical device of the above character, adapted to

22
accomplish among others all of the objects and advantages above set forth.

As many changes could be made in the above construction and many apparently 5 widely different embodiments of my invention could be made, without departing from the scope thereof, I intend that all matter contained in the above description or shown in the accompanying drawing shall be interpreted as illustrative and not in a limiting sense.

Having thus described my invention what I claim as new and desire to secure by Letters Patent is:

15 1. In a device of the character described, a lamp shade capable of adjustment to any desired angle relative to the longitudinal axis of the bulb and adapted to be attached directly to the bulb, and a gripping device 20 for the shade comprising a pair of resilient wires each bent back upon itself, and having a twisted connection with the other adapted to form a plurality of similar grip-

ping arms, each arm being bent irregularly to engage the bulb at two points. 25

2. In a device of the character described, a lamp shade capable of adjustment to any desired angle relative to the longitudinal axis of the bulb and adapted to be attached directly to the bulb, and a gripping device 30 for the shade comprising a pair of resilient wires each bent back upon itself, and having a twisted connection with the other adapted to form a plurality of gripping arms, each arm being bent irregularly to 35 engage the bulb at two points, and means passing through the twisted connection of said arms for securing the gripping device to said shade.

In testimony whereof I affix my signature 40 in presence of two witnesses.

JAMES W. DUNHAM.
